UNITED STATES PATENT OFFICE.

WILLIAM F. PUTNAM, OF CLEVELAND, OHIO.

FOOT-SHIELD FOR FLOORS.

SPECIFICATION forming part of Letters Patent No. 634,956, dated October 17, 1899.

Application filed January 7, 1899. Serial No. 701,507. (No model.)

To all whom it may concern:

Be it known that I, WILLIAM F. PUTNAM, a citizen of the United States, residing at Cleveland, in the county of Cuyahoga and State of Ohio, have invented a certain new and useful Improvement in Foot-Shields for Floors, of which the following is a full, clear, and exact description, reference being had to the accompanying drawings.

10 This invention is peculiarly useful for street-cars and omnibuses, where it serves to protect the feet of the passengers who are sitting and may also serve to increase the available floor-space upon which other passengers may stand or walk. It is, however, useful in many other places--as, for example, in auditoriums, where people are obliged to pass in front of but close to other people who are sitting, and in hacks, carriages, &c.

20 The invention consists of a covered foot-shield secured to the floor close to a seat or seats and open on that side which faces said seat or seats.

It also consists in a foot-shield substantially as described, wherein the top of said shield is an extension of the floor in front of said shield.

It also consists in the more specific combinations of parts hereinafter described, and 30 pointed out definitely in the claims.

In the drawings, Figure 1 is a perspective view of the interior of a street-car equipped with my invention. Fig. 2 is a transverse sectional view of the floor of said car.

35 A A represent the seats of a street-car, which extend longitudinally on both sides of the car. The distance across the aisle between said seats is commonly about four feet, and the seats are commonly about eighteen inches 40 above the floor. When the passengers sit in comfortable positions, their feet project into the aisle about fifteen inches, more or less, wherefore there remains for the comfortable accommodation of the passengers who are 45 standing or walking considerably less than half the width of the aisle. The result is that the passengers who are sitting are especially liable to have their feet trampled upon. To prevent this unpleasant result, a covered 50 shield B is secured to the floor in front of the seats, which shield is open on that side which faces said seats. The passenger sitting in the

seat puts his feet under the shield, whereby they are in a large measure protected. In the best construction the floor of the car immediately in front of the seats and for about fifteen inches, more or less, outward therefrom may be the customary eighteen inches, more or less, below the tops of the seats. The floor D beyond this part C is two inches, more or less, higher than the floor C, and the top b of the foot-shield is, in effect, an extension of the floor D toward the seats, which extension or top of the shield is about five inches, more or less, in width. It is believed that this top of the shield should not be horizontal, but should be inclined upward toward the seat at such an angle that the edge thereof which is nearest the seats is about two and three-fourths inches above the floor C.

70 The dimensions heretofore given are the dimensions of what in my judgment is the most practical embodiment of the invention; but I have no intention of limiting the invention to these dimensions. They may be varied to any extent desired. In the specific embodiment of the invention shown the foot-shield is made of sheet metal consisting of a top b, the integral vertical front side b', and a horizontal foot on the lower edge of said part b', by which the shield is secured to the floor. The edge of the top which is nearest the seats 80 may be supported at suitable intervals by posts F.

Having described my invention, I claim—

85 1. A seat, and an aisle or passage-way in front thereof in which a person may stand, combined with a covered foot-shield located on that side of the aisle or passage-way next to the seat, and open toward the seat, and adapted to receive the feet of the person in the seat, which are thus prevented from being stepped on and do not obstruct the aisle or passage-way, substantially as and for the purpose specified.

90 2. The combination of a seat, a floor in front thereof, a shield overhanging the floor immediately in front of the seat, the upper side of said shield forming a part of the surface adapted to be walked upon in front of the seat, substantially as and for the purpose specified.

95 3. A covered foot-shield supported above a floor close to a seat or seats and open on that side which faces said seat or seats, the top of

said shield being an extension, toward the seats, of the floor which is in front of said shield, substantially as and for the purpose specified.

5 4. The combination with a floor C, a seat resting thereon, a floor D some distance in front of the floor C, which floor D is above the level of the floor C and is extended at a slight angle upward a short distance toward the 10 seats and over the floor C, substantially as and for the purpose specified.

5. The combination of a floor, seats resting thereon, a sheet-metal foot-shield consisting of a slightly-inclined top, a front end and a 15 foot projecting forward therefrom, whereby the shield is secured to the floor, and posts supporting the edge of the top which is nearest the seats, and a floor outside of the shield and substantially at the same level as the 20 front edge of said shield, substantially as and for the purpose specified.

6. In a street-car, the combination with the

seats, the floor directly in front of said seats, and a covered shield which is open on the side which faces said seats, and a floor in front of 25 said shield, the top of which is substantially of the same level as the top of the front edge of said shield, substantially as and for the purpose specified.

7. In a street-car, the combination with the 30 seats running lengthwise of both sides of the car, the floors directly in front of and adjacent to said seats, and the intermediate floor, with foot-shields which are lateral extensions toward the seats of said intermediate floor 35 and overhang the floors adjacent to the seats, substantially as and for the purpose specified.

In testimony whereof I hereunto affix my signature in the presence of two witnesses.

WILLIAM F. PUTNAM.
